UNITED STATES PATENT OFFICE

JOHN W. THOMPSON, OF OAK PARK, ILLINOIS, ASSIGNOR TO MARSHALL FIELD & COMPANY, OF CHICAGO, ILLINOIS, A CORPORATION OF ILLINOIS

MECHANICAL TOY

Original application filed August 13, 1926, Serial No. 128,941. Divided and this application filed April 28, 1928. Serial No. 273,741.

My invention relates to improvements in mechanical toys and more especially the type having a platform mounted on wheels and adapted to be drawn on the ground, and having mounted thereon a plurality of objects attractive to the eye which are moved through connections with the rotating axle to create a combined visual effect.

This application is a division of my former application, Serial No. 128,941, filed August 13, 1926, for improvements in "mechanical toys."

One of the objects of my invention is to provide a platform, mounted on wheels and axle, and which forms a support for a plurality of movable objects which may be either animate or geometrical, or a combination of these, each having a reversing movement and so positioned relatively to each other that they, collectively, create a novel visual effect.

Another object of my invention is to provide a mechanical toy of this type, the objects mounted thereon being driven through the instrumentality of mechanism connected with the rotating axle so as to give the desired mechanical movement.

Another object of my invention is to provide a driving means for this type of mechanical toy, comprising mutilated gearing which is adapted to mesh with other gear elements so as to alternately drive the mounted objects in a given direction and allow them to be moved in a reverse direction when not in mesh.

In my invention I have provided a platform mounted on wheels and axle and on which two animate objects are mounted for combined movement but in which the driving power from the axle is imparted to only one, the second object deriving its motion from the first. In this case also I have provided a mutilated gear which drives in one direction when in mesh but allows a reverse movement through the instrumentality of spring means when the blank portion of the gear is presented.

The objects of my invention will be more fully understood from the following detail description, reference being had to the accompanying drawing, in which—

Figure 1 is a side elevation, partly in cross section of a device constructed in accordance with my invention in which movement in one direction is effected by spring means.

By referring to the drawing it will be noted that my invention comprises a platform 30 mounted on axle 31 and wheel 32. On the under side of platform 30 a slideway 33 is provided which is adapted to receive the rack member 34, the rack member being provided at one end with a pedestal 35 on which is mounted an animal, such as a donkey designated at 36. At the opposite end of the platform is mounted a spring plate 37 attached by rivets such as those shown at 38, on the other end of which is mounted a man, such as a clown 39, in a position to give the effect of pulling the donkey, the arms of the clown and the donkey being connected by an elastic band 40. Mutilated gear 42 is fixed on the axle 31 and is adapted to mesh with the rack element 34 so as to move the latter to the right, as shown in the drawing, together with the donkey against the elastic tension of the band 40, and later to allow a release of the rack element so that it may return in the slide under the influence of the elastic band.

In operation, the ground wheel is adapted to rotate clockwise to move the donkey to the right at which time he pulls the clown forward, apparently resisting this movement through the connection 40, the clown being free to move by virtue of the resilience of the spring metal plate 37. When the gear rotates to the point where it no longer meshes with the rack, the rack is free to slide rapidly to the left, as shown in the drawing under the influence of the elastic band 40 and the spring 37 on which the clown is mounted. This operation gives the appearance of the donkey yielding to the pull of the clown.

The above detailed description and the accompanying drawing illustrate the preferred embodiment of my invention, the scope of which, however, is set forth in the appended claims.

I claim:

1. A toy comprising a platform, wheels and axle for said platform, a mutilated gear on said axle, a sliding object on said plat-

form, a rack connected to said object in mesh with said gear, a second object yieldingly fixed on said platform and an elastic means connecting said objects.

- 5 2. A toy comprising a platform, wheels and axle, an object yieldingly fixed on said platform, a second object mounted for reciprocation on said platform, elastic means connecting said objects urging said objects in approaching directions, and gearing on said axle and object, alternately in and out of mesh when said axle rotates, to alternately move said second object in one direction against the opposition of said elastic means
- 10 15 and to leave it free to return under the influence of said elastic means, said first object deriving movement from said elastic means when said second object moves away from said first object.
- 20 3. A toy comprising a platform, wheels and axle for said platform, a spring mounting on said platform and an object fixed to said spring mounting, a second object on said platform mounted for reciprocation, means connecting said second object with said axle to derive movement therefrom in a direction away from said first object at one period, said second object being disconnected from said axle for another period, and elastic
- 25 30 means connecting said first and second objects tending to move said objects in approaching directions.

Signed at Chicago, Illinois, this 14th day of April, 1928.

JOHN W. THOMPSON.
